The ornamental design for a multifunction electrode pad as shown and described.

DESCRIPTION

FIG. 1 is a top plan view of a multifunction electrode pad showing only the apex pad of our new design;

FIG. 2 is a bottom plan view thereof;

FIG. 3 is a front elevation view thereof;

FIG. 4 is a rear elevation view thereof;

FIG. 5 is a side elevation view thereof;

FIG. 6 is a side elevation view thereof;

FIG. 7 is a top plan view of the multifunction electrode pad showing only the sternum pad;

FIG. 8 is a bottom plan view thereof;

FIG. 9 is a front elevation view thereof;

FIG. 10 is a rear elevation view thereof;

FIG. 11 is a side elevation view thereof;

FIG. 12 is a side elevation view thereof;

FIG. 13 is an illustration of the apex pad on a person;

FIG. 14 is an illustration of the sternum pad on a person; and, FIG. 15 is an illustration of sternum pad and the apex pad of the multifunction electrode pad with integrated 12-lead ECG acquisition on a person.
